[57] **CLAIM**

The ornamental design for a press for holding a pair of relined dentures for curing, substantially as shown and described.

DESCRIPTION

FIG. 1 is an elevational view of a press for holding a pair of relined dentures for curing, showing my new design;

FIG. 2 is an elevational view thereof, rotated clockwise 90° from the position of FIG. 1;

FIG. 3 is a top plan view thereof;

FIG. 4 is a bottom plan view thereof, positioned the same as FIGS. 1 & 3;

FIG. 5 is an exploded vertical sectional view thereof taken along line 5—5 of FIG. 3, partially in elevation.

FIG. 1.FIG. 2.FIG. 3.FIG. 4.
